UNITED STATES PATENT OFFICE.

WILLIAM F. DONOVAN, OF TOLEDO, OHIO, ASSIGNOR TO THE LIBBEY GLASS COMPANY, OF TOLEDO, OHIO, A CORPORATION OF OHIO.

DESIGN FOR A DISH.

No. 38,512.

Specification for Design.

Patented April 9, 1907.

Application filed June 30, 1906. Serial No. 324,285. Term of patent 7 years.

To all whom it may concern:

Be it known that I, WILLIAM F. DONOVAN, a citizen of the United States of America, residing at Toledo, in the county of Lucas and State of Ohio, have invented a certain new, original, and ornamental Design for a Dish, of which the following is a specification, reference being had therein to the accompanying drawing, forming part thereof.

The figure is a perspective view of a dish, showing my new design.

I claim—

The ornamental design for a dish, as shown

WILLIAM F. DONOVAN.
